UNITED STATES PATENT OFFICE.

SAMUEL S. STEVENS, OF HOOSICK, NEW YORK.

PULP-ENGINE.

SPECIFICATION forming part of Letters Patent No. 634,039, dated October 3, 1899.

Application filed February 9, 1898. Serial No. 669,630. (No model.)

To all whom it may concern:

Be it known that I, SAMUEL S. STEVENS, a citizen of the United States, residing at North Hoosick, county of Rensselaer, and State of New York, have invented certain new and useful Improvements in Pulp-Engines, of which the following is a specification.

The invention relates to such improvements; and it consists of the novel construction and combination of parts hereinafter described and subsequently claimed:

Reference may be had to the accompanying drawings and the letters of reference marked thereon, which form a part of this specification.

Similar letters refer to similar parts in the several figures.

Figure 1 of the drawings is a plan view of my improved engine. Fig. 2 is a view of the same in side elevation with the side wall broken away at the middle and at one end. Fig. 3 is a vertical cross-section taken on the broken line 3 3 in Fig. 1. Fig. 4 is a view in side elevation of the bed-plate box and contents, the vertical side walls of the box being removed. Fig. 5 is a top plan view of the parts shown in Fig. 4. Fig. 6 is a vertical cross-section taken on the broken line 6 6 in Figs. 4 and 5. Fig. 7 is a plan view of the worm-sleeve detached. Fig. 8 is a similar view of a clutch-section detached. Fig. 9 is a vertical cross-section taken on the broken line 9 9 in Fig. 5.

A is the mixing-vat, which is divided by the two parallel midfellows A' into circulating-channels. The middle or return channel A² connects with and is common to the two side or roll channels A³, each one of which contains a beater-roll A⁴, fixed upon the same shaft A⁵, having end journals A⁶ rotary in bearings A⁷, fixed in cross-beams supported by the uprights A⁸. Rotary movements can be communicated to the shaft and rolls by means of the belt-pulley A⁹, fixed upon the shaft. The bed of the vat is inclined, so as to form a back-fall on that side of each roll from which the pulp flows and a descending incline on the opposite side in the usual manner. Beneath each roll, in a recess in the bed, is located a detachable box B, containing the bed-plate B', provided with the usual bed-plate knives B².

The principal objects of my invention are to facilitate the mixing in a pulp beating and mixing engine and to level and adjust the bed-plate relatively to its coöperating-roll, whether the engine is in operation or at rest.

My invention consists of an inclined bottom in the return-channel extending approximately from the back to the front of the vat, with elevated connecting-channels between the roll and return channels, and of lifting-screw supports for the adjustable bed-plates, with exteriorly-accessible means for operating the screws, as hereinafter more fully explained and claimed.

When a stratifying apparatus is applied to a pulp-engine, the stratifying-channels, being superposed one above the other, necessitate raising one of them above the normal bed or bottom of the vat. I have ascertained that by raising both of them and inclining the bottom of the return-channel from the raised channels to the front of the vat the flow of the stock will be greatly facilitated.

Referring to Fig. 3 of the drawings, C is the elevated bed of the upper channel leading from one of the beater-rolls, and C' is the elevated bed of the lower channel, which leads from the other roll beneath the upper channel.

C² and C³ are respectively the upper and lower discharge-openings, through which the two divisive currents enter the return-channel in horizontal strata, one above the other.

It will be seen that the lower bed C' is raised above the normal bottom C⁶ of the vat, and I give the bottom C⁶ of the return-channel an incline extending from the bed C' to the normal bed of the vat at its front end, as indicated by the dotted line C⁶ in Fig. 2.

My improved means for leveling and adjusting the bed-plate and comprising the plate B' and knives B², which coöperate with the beater-roll, consist of the screws B³ and B⁴, which are secured by bolts B⁵ to the bottom of the plate. Each screw is provided with a nut B⁶, bearing upon a plate or plate-ring B⁷, secured to the bed of the vat. The nuts are provided with a worm-gear B⁸, engaged by a worm. The gear on screw B⁴ is engaged by worm D on the shaft D', and the gear on the other screw B³ is engaged by the worm D' on the sleeve D³. The shaft passes entirely

through the sleeve and is adapted to turn in the latter. The sleeve and shaft together turn in the bearing-blocks D¹. The projecting end of the shaft (seen at the left-hand end in Fig. 4) is provided with a feather or spline S, Fig. 9, and supports the clutch-section D⁵, interlockable with the other section D⁶, fixed upon the sleeve. I have shown the extreme end of the shaft screw-threaded and provided with a small lock-nut D⁷, by which the clutch can be locked in engagement, as shown in Figs. 4 and 5. The sleeve is also provided with a worm-gear D⁸, engaged by the worm D⁹, fixed upon the upwardly-projecting worm-shaft D¹⁰, supported in suitable bearings D¹² on the outer side of the vat and provided with an operating-handle D¹³.

The operation of the adjusting mechanism is as follows: To raise or lower both ends of the knife-bed plate equally, turn the hand-wheel D¹³ in the required direction. To raise or lower one end of the plate relatively to the other, disengage the clutch connection between the shaft and sleeve and bring the two ends to the desired levels relatively to each other by the hand-wheel, which will operate the sleeve to raise or lower one end relatively to the other until the desired relative position is obtained, then reengage the clutch connection and by means of the hand-wheel raise or lower both ends to the desired level.

What I claim as new, and desire to secure by Letters Patent, is—

1. In a pulp beating and mixing engine having a pair of roll-channels and an intermediate return-channel, the combination with a beating and current-producing mechanism located in the roll-channels; of elevated channels for carrying the moving stock from the roll-channels to the return-channel; and an inclined bottom for the return-channel descending in the direction of the moving stock approximately from one end of the vat to the other, substantially as described.

2. In a pulp-engine, the combination with a beating-roll; of a bed-plate movable to and from the roll; a pair of plate-supporting screws, each provided with a worm-gear; a horizontal worm-shaft engageable with the worm-gear on the screws; a worm-gear fixed on the worm-shaft; an upwardly-projecting worm-shaft engageable with the gear on the horizontal shaft; and means for turning the upwardly-projecting shaft, substantially as described.

3. In a pulp-engine, the combination with a beating-roll; and bed-plate movable to and from the roll; of plate-leveling mechanism consisting of a pair of plate-supporting screws, each provided with a worm-gear; a worm-shaft engageable with the gear on one of the screws; a worm-sleeve engageable with the gear on the other screw; and revolvably supported on the worm-shaft; a clutch splined on the worm-shaft and detachably engageable with the worm-sleeve; and means for communicating revoluble movements to the sleeve, substantially as described.

In testimony whereof I have hereunto set my hand this 15th day of January, 1898.

S. S. STEVENS.
